PENCIL CASING

Application filed October 14, 1930. Serial No. 488,595.

This invention relates in general to pencil casings or holders, and one object of the invention is to provide a novel and improved device of this character which shall make it possible to completely utilize or use up ordinary lead pencils comprising a rod or stick of lead encased in wood or the like. Generally, such lead pencils, as the result of repeated sharpening, become so short as to be useless, that is, the pencils eventually become so short that they cannot be conveniently gripped for writing.

Another object of the invention is to provide a holder or casing for pencils within which the pencil may be clamped with one end projecting from the holder, said holder including means for sliding the lead outwardly from the wooden casing of the pencil, the holder serving as an extension grip for manipulating the pencil during writing operations and permitting utilization of the entire lead.

Other objects are to provide such a pencil holder or casing including two relatively rotatable and longitudinally movable sections one of which has means for clamping a pencil therein, while the other has means for engaging the lead in the pencil and forcing the lead out of the pencil upon relative longitudinal movement of the sections; to provide in such a pencil holder novel and improved means for adjustably clamping a pencil therein; to provide such a holder which shall be simple and inexpensive in construction; to provide a pencil holder so constructed as to be capable of first loosening the lead in a pencil for sliding movement, and thereafter propelling the lead from the pencil to compensate for shortening thereof by use, and to obtain other advantages and results as will be brought out by the following description.

Referring to the accompanying drawings, in which corresponding and like parts are designated throughout the several views by the same reference characters,

Figure 1 is a vertical longitudinal sectional view through a pencil holder embodying my invention, showing the same utilized for initially loosening the lead in a pencil;

Figure 2 is a side elevation thereof;

Figure 3 is a view similar to Figure 1, showing the holder as it is normally used;

Figure 4 is a horizontal sectional view, on the line 4—4 of Figure 1;

Figure 5 is a detached side elevation of the lead-propelling rod, and

Figure 6 is a fragmentary vertical longitudinal sectional view through the pencil holder, showing a modified form of pencil clamping means.

Specifically describing the embodiment of the invention shown in Figures 1-5, inclusive, the holder comprises a main tubular casing section 1 to receive therethrough a wood encased lead pencil 2. One end of the casing section is exteriorly screw threaded at 3 and has an interior circumferential groove 4 and a corresponding exterior rib 5 inwardly of the screw threads 3. Within the groove 4 is arranged a split metal ring 6, and threaded upon the end of the casing section is a clamping sleeve 7, the inner end 8 of which abuts the rib 5 when the sleeve is screwed upon the casing section. The casing section 1 is formed with a plurality of longitudinal slits 9 which intersect the rib and groove 4 and 5 so that the walls of the casing section may be compressed inwardly.

In securing a pencil in the casing section, the sleeve 7 is unscrewed and the pencil is slipped into the casing past the split ring 6. The sleeve 7 is then screwed onto the casing section until the end 8 thereof engages the rib 5, which causes the walls of the casing section to be compressed so as to force the split ring 6 tightly into contact with the pencil and thereby clamp the pencil in the casing.

The other end of the casing section 1 is interiorly screw threaded at 10 to receive an actuating member 11. This member 11 has both ends exteriorly screw threaded at 12 and 13 to fit the threads 10 of the casing section 1, so that the member can be screwed into the casing section. The ends of the actuating member have the respective axial recesses 14 and 15, at the bases of which are formed sockets 16 and 17 to removably receive a push rod 18 and a lead-propelling rod 19. A cap 20 carrying an eraser 21 may be screw threaded upon either end of the actuating member.

For the purpose of initially loosening the lead 22 in the lead pencil 2, that is, to initially break the hold of the glue upon the lead, the push rod 18 is fitted into the corresponding socket 17 and the actuating member is screwed into the casing section 1 so that said push rod engages the end of the lead, as shown in Figure 1. Relative rotation of the casing section 1 and the actuating member 11 will then cause relative longitudinal movement of the casing sections which in turn will exert pressure on the lead and loosen it in the casing of the pencil. The short push rod 18 is utilized to avoid possibility of the rod being bent or distorted during this operation.

The actuating member is then removed from the casing section 1 and reversed, whereupon the lead-propelling rod 19 is inserted in the socket 16 and the actuating member is screwed into the casing section until the rod 19 engages the lead. The cap 20 is applied to the projecting end of the actuating member, as shown in Figure 3 of the drawings. Upon relative rotation of the actuating member and the casing section 1, the lead 22 will be propelled from the end of the wooden body of the pencil, as shown in Figure 3 of the drawings.

Pencils of different lengths may be readily accommodated in the holder due to the adjustable clamp means, and the lead in the pencils may be exposed for use either by sharpening as usual, or by manipulation of the actuating member 11, or both.

Another form of adjustable clamping means for securing the pencil in the casing is shown in Figure 8 of the drawings. In this form of the invention the casing has an exterior circumferential rib or projection 35 from which are punched inwardly of the casing a plurality of teeth or prongs 36. The extremity of the casing section is screw threaded at 37 and has screwed thereon a nut 38 like the nut 7, the inner end of said nut being adapted to engage the rib 35. To clamp the pencil in the casing, the nut 38 is loosened and the pencil is slipped into the casing past the prongs 36. The nut is then screwed on the casing until its inner end engages the rib 35, which causes the prongs to be pressed into the body of the pencil so as to securely hold the pencil in the casing. The perforations produced by the punching of the prongs 36 from the casing render the casing sufficiently contractible to permit the prongs to be so pressed into the pencil, said perforations serving the same function as the slits 9 shown in Figures 1-3, inclusive.

Obviously many modifications and changes may be made in the details of construction of the pencil holder without departing from the spirit or scope of the invention, and therefore I do not desire to be understood as limiting myself except as required by the following claims when construed in the light of the prior art.

Having thus described the invention, what I claim is:

1. A pencil holder comprising a casing to receive in one end thereof a pencil which includes a body and a lead slidable therein, means on said end of the casing section to clamp said pencil against movement therein, and means in said casing to engage and push said lead from said body. 70

2. A pencil holder comprising a casing to receive in one end thereof a pencil which includes a body and a lead slidable therein, means on said end of the casing section to clamp said pencil therein, and means screw threaded in the other end of said casing to engage and push said lead from said body upon relative rotation of said means and said casing section. 75 80

3. A pencil holder comprising a casing to receive in one end thereof a pencil which includes a body and a lead slidable therein, said end being exteriorly screw threaded, formed with longitudinal slits and having an exterior rib intersected by said slits, a clamping sleeve screwed on said end of the casing to engage said rib and compress the walls of said casing into contact with the body of said pencil to clamp the pencil in the casing, and means in said casing to engage and push said lead from said body. 85 90 95

4. A pencil holder comprising a casing to receive in one end thereof a pencil which includes a body and a lead slidable therein, said end being exteriorly screw threaded, formed with longitudinal slits and having an interior circumferential groove adjacent said slits, a split ring in said groove, and a clamping sleeve screwed on said end of the casing to compress said split ring into contact with the body of said pencil to clamp the pencil 100 105 in said casing.

5. A pencil holder comprising a casing to receive in one end thereof a pencil which includes a body and a lead slidable therein, said end being exteriorly threaded and having an exterior circumferential rib at the inner extremity of the threads, the casing having a plurality of inwardly projecting prongs stamped from said rib, a clamping sleeve screwed on the said end of the casing to engage said rib and compressing the walls of the casing to force said prongs into the body of said pencil and clamp the pencil in the casing, and means in said casing to engage and push said lead from said body. 110 115 120

JOHN SCHNEIDER.
